UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRATT, OF BLOOMFIELD, NEW JERSEY, RECEIVERS.

ELECTRIC SIGNALING.

1,132,568.

Specification of Letters Patent. Patented Mar. 23, 1915.

Application filed October 31, 1907. Serial No. 400,132.

To all whom it may concern:

Be it known that I, REGINALD A. FESSENDEN, a citizen of the United States, residing at Brant Rock, in the county of Plymouth,

5 State of Massachusetts, have invented certain new and useful Improvements in Electric Signaling, of which improvements the following is a specification.

My invention relates to method of and 10 apparatus for high speed signaling and more particularly high speed wireless telegraphy.

In the accompanying drawings forming a 15 part of this specification Figure 1 shows apparatus for sending and Fig. 2 apparatus for receiving embodying my invention.

The invention herein described has for its object the transmission and receipt of a 20 large number of words per minute between signaling stations.

In the practice of my invention I prefer to use an ordinary Wheatstone transmitter in connection with a method for generating 25 electromagnetic waves practically continuously at the sending end and to make the perforated tape change the frequency of the waves without interrupting their continuity. At the receiving end I prefer to use my heterodyne receiver as more fully described in my Patent No. 1,050,441, Jan. 14, 1913, though any other suitable type may be used and to record the sound produced on a phonograph of any type, such as the Poulsen or Edison phonograph.

30 The messages on being received at the sending end are transferred to the perforated tape which is sent through the machine at a high rate of speed, for example 500 words per minute. The phonograph at 35 the receiving end is run at a speed much above normal, for example 20 revolutions per second, while the message is being received. The phonograph record is then handed to an operator who by running at 40 a speed of say one revolution per second gets the telegraph messages at the rate of only 25 words per minute and transcribes it in the usual form. Means are provided for ascertaining whether the message is being 45 recorded on the cylinder.

In Fig. 1, 11 is an antenna grounded at 12, 13 is a compressed air spark gap, 14 a variable inductance, 15 a condenser, 16 a source of continuous current, 17 an adjustable re-

sistance, the whole forming a system for 55 producing practically continuous high frequency oscillations as described in U. S. Patent 706,742.

18 is a Wheatstone transmitter, 19 being a strip of perforated paper on which the 60 message is embossed and 20 the relay of the Wheatstone transmitter.

The relay of the Wheatstone transmitter operates to cut out the portion 21 of the inductance 14, thus changing the frequency 65 of the emitted waves by a small amount, preferably about $\frac{1}{6}$ of one per cent.

In Fig. 2, 22 is the antenna, grounded at 23; 24, 25 the primary and secondary of a transformer, 26 is a small coil mounted on 70 a telephone diaphragm 27, 28 an electromagnet excited by a source of high frequency currents of nearly the same frequency as the received waves, such for example as a high frequency alternator 29. 75 This will cause beats with the received oscillations in cases where this is desired or necessary, and such beats effect the diaphragm 27 as will be evident. 30 is a phonograph trumpet and 40 a phonograph of the 80 Edison type.

41 is a receiver, with a rubber-ear piece 42, which can be attached to the phonograph to determine if the messages are being recorded.

If desired the phonograph needle may be mounted directly on the diaphragm 27, but as this modification is an obvious equivalent it is not shown.

It is found that by using the present apparatus in the manner described the effects of static disturbances are eliminated. Such disturbances are almost invariably pulses of low frequency, say 40 or 50 per second. If the signaling waves are emitted at a high 95 spark or group frequency, say 10,000 per second, they can be recorded at the same speed with the static disturbances of a frequency of from 40 to 50 or the like superimposed thereon. Then by reproducing the 100 recorded waves at $\frac{1}{10}$ of the recording speed the signaling waves are produced at a speed of 1000 per second, giving a high musical note, but the static disturbances are reproduced at a speed of 4 or 5 per second, too 105 low to be audible. Their effect is therefore wholly eliminated.

Having thus described my invention and

illustrated its use, what I claim as new and desire to secure by Letters Patent is the following:

1. The method of electric signaling, which comprises sending the signaling waves at high frequency, recording said waves along with the effects of disturbing pulses, and then reproducing the record at a lower speed, whereby the effect of the disturbing impulse is eliminated.
2. The method of wireless signaling, which comprises sending the signaling waves at high frequency, recording said waves and the effects of disturbing impulses at high speed, and then reproducing the record at a speed so low as to eliminate the effect of the disturbing impulse but leaving the signaling waves audible.

3. Apparatus for transmitting and translating intelligence, comprising means for producing signaling waves at high frequency, and means for recording said waves and the effect of disturbing impulses at high speed, said recording means being arranged to reproduce the record at a lower speed in order to eliminate the effect of the disturbing impulse but leaving the signaling waves audible.

In testimony whereof I have hereunder signed my name in the presence of the subscribed witnesses.

REGINALD A. FESSENDEN.
